UNITED STATES PATENT OFFICE.

EDWARD P. DAMERON, OF DENVER, COLORADO.

DENTAL AND SURGICAL INSTRUMENT.

1,240,320.

Specification of Letters Patent. Patented Sept. 18, 1917.

Application filed October 10, 1916. Serial No. 124,796.

To all whom it may concern:

Be it known that I, EDWARD P. DAMERON, a citizen of the United States, residing at Denver, in the county of Denver and State 5 of Colorado, have invented certain new and useful Improvements in Dental and Surgical Instruments, of which the following is a specification.

This invention relates to dental and surgical instruments, and its object resides in providing a clamp of novel construction which is adapted to depress and hold the tongue and extend the cheeks of a patient, whereby to facilitate the performance of dental and 15 pharyngeal operations.

With the above object in view, my invention comprises a pair of relatively adjustably connected jaws provided with leaf-shaped blades which are adapted to simultaneously engage the tongue and chin of the 20 patient.

Secured to the upper jaw of the clamp, which carries the tongue-blade, are a pair of resilient spreaders which when the instrument is in its operative position, engage the cheeks of the patient for the purpose of separating them from the teeth.

The adjustable connection between the two jaws comprises a pair of slidably related 30 members one of which has a series of ratchet teeth and the other one of which carries a spring-pressed pawl for engagement with said teeth.

In the use of my invention, the tongue of 35 the patient is depressed and firmly held against upward movement and the cheeks are at the same time extended whereby to afford ready access to the teeth and the throat of the patient.

A dentist or surgeon is thus enabled to 40 use both hands in performing dental and pharyngeal operations and he may operate without being disturbed by a movement of the tongue, and, in dentistry, without transference of the saliva from the tongue and 45 cheeks to the teeth.

The instrument has the additional advantage that it may be applied and held in place for a considerable period, without annoyance to the patient and without injury to 50 the parts with which it comes in contact.

An embodiment of my invention has been shown in the accompanying drawings in the various views of which like parts are similarly designated, and in which—

Figure 1 is a sectional view of a human

head showing the method of applying the instrument,

Fig. 2, a plan view of the instrument, drawn to an enlarged scale, 60

Fig. 3, a similar view of the instrument without the cheek-distending attachment,

Fig. 4, a side elevation of the instrument shown in Fig. 2, and

Fig. 5, an enlarged section taken along the 65 line 5—5, Fig. 4.

Referring to the drawings, the reference numerals 5 and 6 designate respectively the upper and lower jaws of the clamp.

The jaw 5 consists of a blade 7 of thin resilient metal, which is secured at the end of a stem 8 provided with a series of ratchet teeth 9. The blade is curved to fit the surface of the tongue in a depressed condition and it has a central slot 10 to expose a portion of the tongue against which it presses. 70

The stem 8 carries adjacent its upper end, the cheek-distending appliance which consists of a pair of laterally diverging, curved wire-springs 12 the outer ends of which are 75 coiled to prevent injury of the parts with which they come in contact.

When the instrument is used for pharyngeal operations only, the cheek-distending appliance is omitted and the tongue blade is 80 lengthened to extend to the rear end of the tongue as shown in Fig. 3 of the drawings.

The lower jaw 6 of the instrument consists of a blade 13 of thin metal curved to fit around the chin of the patient and attached at the lower end of a tubular stem 14 in which the toothed stem 8 of the upper jaw is slidably fitted.

A pawl 15 fulcrumed upon the tubular stem has a detent which extends through a 95 slot in the tube to engage the teeth on the stem of the upper jaw.

The pawl has a thumb piece to facilitate its adjustment and a spring 16 applied between the thumb-piece and the tubular stem 100 operates to yieldingly maintain the detent in engagement with the teeth of the stem 8.

The method of using the instrument has been shown in Fig. 1 and will be readily understood without further explanation. 105

Having thus described my invention I desire it understood that variations in the form and arrangement of the parts of the clamp, may be resorted to within the spirit of the invention as defined in the following 110 claims:

1. An instrument of the character de-

scribed comprising a clamp composed of a pair of coöperative jaws adapted to engage the tongue and chin of a patient and an appliance adapted to distensibly engage the cheeks of the patient while one of said jaws engages the tongue of the same.

2. An instrument of the character described comprising a clamp composed of a pair of coöperative jaws adapted to engage the tongue and chin of a patient, and an ap-

pliance consisting of a pair of spring-members adapted to engage the cheeks of a patient whose tongue is depressed by one of said jaws.

In testimony whereof I have affixed my signature in presence of two witnesses.

EDWARD P. DAMERON.

Witnesses:

G. J. ROLLANDET,
L. RHOADES.
